UNITED STATES PATENT OFFICE.

JETER JONOR, OF NEW BRITAIN, AND JOHN TOMCZEWSKI, OF NEWINGTON, CONNECTICUT.

SAFETY DEVICE FOR PRESSES.

1,371,426.

Specification of Letters Patent. Patented Mar. 15, 1921.

Application filed October 4, 1919. Serial No. 328,538.

To all whom it may concern:

Be it known that we, PETER JONOR and JOHN TOMCZEWSKI, citizens of Poland, residing said JONOR at New Britain and said 5 TOMCZEWSKI at Newington, in the county of Hartford and State of Connecticut, have invented certain new and useful Improvements in Safety Devices for Presses, of which the following is a specification.

10 Our invention relates to improvements in safety devices for presses, of the form used as a guard or protection for the operator of a punch press or any of the various forms of presses used for punching and forming 15 operations and particularly to prevent injury to the hands of the operator, and the object of our improvement is to produce a device that is simple and reliable for the purpose specified, and which, furthermore, 20 is particularly effective and efficient in that it involves in use a positive connection for the hands of the operator with the moving part of the press whereby the hands are positively pulled away from the position of 25 danger, between the two dies, before the dies come together in case the operator failed to himself remove the hands from the position of danger, and which device permits of the free use of the hands and arms 30 to the extent necessary for such handling of the work as may be necessary between the operations of the dies.

In the accompanying drawing:

Figure 1 is a front elevation of a press 35 that is equipped with our improved safety device.

Fig. 2 is a similar view, on an enlarged scale, of the safety device shown in Fig. 1 and some of the associated parts of the 40 press.

Fig. 3 is a similar view, with the parts in a different position from that shown in Fig. 2.

The press 10 shown and to which our improved safety device is applied is a conventional representation of a drop press or power press of any of the usual forms, comprising the bed 11 that supports the fixed die 12 at the upper middle portion in the usual manner and also supports in the usual manner a pair of uprights 13 that extend upwardly from the said bed 11 positioned one on each side of the said fixed die 12,

that serve as supports and guides for slidably engaging with the movable block 14 55 that supports on the lower face the moving die 15 that co-operates with the fixed die 12.

Mechanism, designated generally by the character 16, serves to raise the block 14 and die 15, being operated by the pulley 17, and 60 which when released permits the block and die to fall in the usual manner or the press may be positively driven by power for both the upward and the downward movement of the moving block 14.

Whatsoever the method may be for operating the moving die, in operating the press, during the period of separation of the dies the operator has occasion to bring either one or both hands in the space between the dies 70 for handling the work and must, in order to avoid injury, withdraw the hand or hands from such position before the dies come together. Accidents happen, resulting in injury to the operator, in cases in which such 75 withdrawing of the hands from the danger zone is left entirely to the action of the operator.

By the use of our invention the operator can withdraw his hands from the danger 80 zone freely, substantially in the same manner as if there were no safety device provided, but in case of neglect on the part of the operator to do so the safety device operates positively to pull the hands away, so 85 that the operator is not relied upon for safe operation.

The manner of effecting this result is as follows:—The device is arranged duplex and symmetrical on the two sides, comprising for each side a cord 18 rove through suitable guide pulleys, connected by the upper end to the moving block 14 and provided on the lower end with a loop 19 or any other means for engaging with the hand 90 20 of the operator, and the parts are constructed and arranged so that the said hand 20 will be pulled away from the path of the moving block 14 in time to prevent being caught between the dies 12 and 15.

As shown, there are two guide pulleys for the cord, comprising for each side an upper pulley 21, positioned to one side and secured to the opposed upright 13 and preferably slightly above the uppermost position of the 105 upper end of the cord 18, and the lower

pulley 22, which, as shown, is supported at about the level of the lower, fixed die 12 and to one side, being supported from the base 10 by a side bracket 23.

5 Sash-cord may be used for the cord 18.

The upper end of the said cord 18 may be secured to an eye, as a screw-eye 24, in the front face of the block 14.

An elongated spring 25 may be provided 10 to take up slack, being secured by the lower end of the bracket 23 and having the upper end 26 secured to the generally upwardly directed body portion 27 of the cord 18.

In some cases the cord may be inclosed 15 by the coils of the spring.

We claim as our invention:—

1. A safety device for presses having a fixed die and a movable die comprising a

cord having one end connected to the movable die, having the other end adjacent the 20 fixed die and provided with means for being secured to the hand of the operator, and guide means for guiding the body portion of the said cord, and the parts being constructed and arranged to pull the said other 25 end away from the said fixed die during the movement of the movable die, suitably to withdraw the hand of the operator away from the danger zone between the two dies.

2. A safety device for presses as described 30 in claim 1 and provided with an elongated spring, connected to the said cord, for taking up slack in the cord during the movements of the movable die.

PETER JONOR.

JOHN TOMCZEWSKI.
